UNITED STATES PATENT OFFICE.

GUSTAV RAU, OF KANSAS CITY, MISSOURI.

AIR-COOLED BLOCK FOR LINING WALLS.

Application filed April 29, 1926. Serial No 105,434.

This invention relates to air-cooled blocks for building the inside walls of stills, ovens, boilers and the like.

The primary object of the invention is to increase the length of life of inside walls for the purpose specified and also to transmit air through the blocks to driers for drying coal.

A further object of the invention is to provide a series of air-cooled blocks embodied in a lining wall or belt having alined openings therethrough in planes at right angles, to set up both horizontal and vertical air flues when the blocks are assembled in the wall structure.

A still further object of the invention is to provide in connection with each of the air-cooled blocks a removable and replaceable nose or surface section which serves to protect the remaining portion of the block in rear thereof, and when said removable nose or section becomes deteriorated by flame or hot gases from the fire in the still, oven, boiler or like device, it may be readily detached and another similar nose or section applied, the stationary part of the block being so constructed that when the nose or section is removed, the wall above will be supported and prevented from falling.

With the foregoing and other objects and advantages in view, the invention consists in the preferred construction and arrangement of the blocks which will be more fully herein-after described and claimed.

In the drawing:

Fig. 1 is a longitudinal vertical section of a furnace, showing a lining wall or belt comprising the improved air-cooled blocks.

Fig. 2 is an enlarged transverse vertical section of a part of a furnace wall and several of the improved blocks applied thereto and illustrating the protective nose of one of the blocks removed.

Fig. 3 is a top plan view of one of the blocks and the protective removable nose therefor.

Fig. 4 is a transverse vertical section on the line 4-4, Fig. 3, looking in the direction of the arrows and particularly showing the communication of the horizontal and vertical air flues of the block.

The improved block, as heretofore indicated, comprises two sections or members, namely, a body 5 and a replaceable nose or surface section 6. The body 5 is formed with a vertical web 7, a lower outward extension 8, and an upper, inward extension 9, both ex-

tensions being disposed in planes at right angles to the web 7. The lower outward extension 8 is thicker than the inward extension 9 and said lower extension 8 is inserted in a groove 10, there being a plurality of the grooves 10 formed in the one end wall 11 of a furnace or other device 12 to which the improved lining or belt comprising the blocks is applied. These grooves 10 continue horizontally in parallel relation through the inner side of the wall 11 and this wall is reduced in thickness to an extent corresponding to the combined thickness of the bodies 5 and protecting noses or surface sections 6 of the several blocks. The upper extension 9 of each block is formed with a lower recess 13 at its free forward edge, said recess extending throughout the length of the said extension and the outer side of the web 7 continues from its point of intersection with the lower side of the extension 9 fully to the bottom of the body 5. Applied over the inner side portions of the block bodies 5 having the extensions 8 and 9 as above specified are the protecting noses of sections 6, the latter having upper, inner flanges 14 of the same dimensions as the recesses or seats 13 and are received in the latter, the lower portions of the noses of sections 6 having outwardly projecting extensions 15 which terminally abut against the lower outer portion of the bodies 5 adjacent to the extensions 8 of the said bodies. The noses or sections 6 are substantially L-shaped in form and contribute, in combination with the bodies 5 and extensions 8 and 9, to form horizontal air flues 16. In the outer free extremities of the extensions 9 vertical air flues 17 are formed and in the extension 15 of the nose or section 6 similar flues 18 are also constructed and alined with the upper vertical flues 17 and open into the horizontal air flues 16. When the blocks comprising the body members 5 and the protecting noses or sections 6 are assembled in a lining or belt formation with relation to the walls of a furnace or other like device, all of the horizontal flues 16 are in alinement and provide continuous air passages, and likewise, all of the vertical flues 17 and 18 are in alinement and form a plurality of vertical air passages, and in connection with the end wall 19 of the furnace or like device a manifold 20 is exteriorly applied over the outlets 21 of the horizontal air flues, the said manifold having a central pipe connection 22 for application thereto of a tubular conducting

pipe connected to a fan or suction means, and whereby the hot air and gases may be drawn from the interior of the furnace and conveyed to a place of storage for coal, to dry the latter. It is also possible to use this withdrawn hot air and gases for other purposes.

It will be seen that the lower reduced portion of each wall to which the lower course of blocks comprising the bodies 5 and noses or sections 6 are applied forms a base support by the construction of a shoulder or ledge 23 as the result of the reduction in thickness of the walls, and the remaining course of blocks above are positively supported in vertical arrangement as shown by Fig. 1. The several block bodies have their outward extensions 8 engaging the grooves 10 of the walls, and these bodies are therefore held in true applied position at all times, or with the webs 7 extending vertically. When the deteriorated or burnt-out noses or sections are removed for replacement by similar noses or sections to remove the inner side of the lining wall or belt, the superposed blocks will not in the least be affected or displaced, owing to the fact that the blocks successively above the lower course of block bodies are held supported on the upper sides of the extensions 9 and thereby the entire wall is maintained in association with the walls of the furnace or other device, and furthermore, when the noses or sections 6 are in association with the bodies 5, they are likewise held on the upper edges of the succeeding noses or sections. It will therefore be seen that the walls have at all times a stable application and will not become loose or disarranged.

As heretofore indicated, the principal feature of the invention is the provision of the air-cooled blocks, or the formation of the horizontal air flues 16 and the vertical air flues 17 at all times in communication with the flues 16, and whereby the whole wall is cooled, with material advantages in the structure of the wall of a furnace or other device, and to this principal advantage is added the convenience in replacing the inner side of the wall which becomes deteriorated or burnt-out, without affecting the remaining portion of the lining or belt, with obvious economy in structures of this character. A further advantage is the provision for drawing heated air and gases away from the lining wall or belt comprising the improved air-cooled blocks and their protective, removable components or noses or sections 6.

The two members of each block, or the body 5 and removable nose or section 6, are both formed of refractory material similar to that used for making high grade firebrick and ordinarily employed for furnace linings, and the particular effect of cooling the lining wall or belt is imposed upon the series of

noses or sections 6 with the result that the latter parts will last materially longer than would be the case if there were no temperature lowering provision in the form of the continuous horizontal and vertical communicating air flues. The overhang of the brick-work is of such extent that it does not bear upon the noses or sections 6, more than half of the brickwork resting on the block bodies. Though it is proposed to standardize the proportions of the two components of each block for the purpose of economy in manufacture, it will be understood that at times it may be desirable to modify the dimensions and proportions thereof to adapt the same to particular applications.

The removable noses or protective sections when withdrawn open the horizontal and vertical air passages and permit the latter to be freed of all accumulation of products of combustion that may lodge therein, so that the air flues or passages may be maintained in unobstructed condition.

What is claimed as new is:

Air cooled blocks for service as components of a lining or belt for and combined with a furnace wall, each block comprising a vertical body member with an upper terminal inwardly projecting extension and a lower terminal outwardly projecting extension, both extensions being at planes at right angles to the vertical body member, and the upper extension having a lower angular inwardly opening corner recess continuing fully over the width of the extension, and a removable and replaceable nose member having a vertical body and a lower outwardly projecting extension which terminally abuts against the inner side of the lower portion of the vertical body of the first named member with the bottom thereof flush with the bottom of the said outward extension of first named member, the upper terminal of the body of the nose member having a flange fitting in and flush with the recess of the inner terminal of the upper inwardly projecting extension of said first named member, the upper inwardly projecting extension of the first named member and the lower outwardly projecting extension of the nose forming a central flue continuing uniformly transversely through the complete block, and the upper inwardly projecting extension of the first named member and the outwardly projecting extension of the nose respectively having a pair of spaced vertical flues opening in to said central flue, whereby when a number of the complete blocks are assembled the said vertical flues become continuous through all the blocks and communicate with the horizontal flues of the blocks.

In testimony whereof I have hereunto set my hand.

GUSTAV RAU.
